Primary Examiner — Derrick E Holland(74) *Attorney, Agent, or Firm* — ZANIP(57) **CLAIM**

The ornamental design for a support for solar panel, as shown and described.

DESCRIPTION

FIG. 1 is a front and top perspective view of a support for solar panel, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion labeled, 'FIG. 9' in FIG. 1;

FIG. 10 is an enlarged view of a portion labeled, 'FIG. 10' in FIG. 1; and,

FIG. 11 is an enlarged view of a portion labeled, 'FIG. 11' in FIG. 2.

The dash dot dash lines in FIGS. 1, 2, 9, 10 and 11 are for the purpose of depicting the cut lines of the enlarged views and form no part of the claim. The dashed broken lines in the figures illustrate the portions of the support for solar panel that form no part of the claimed design.
